SHIFTER CLAMPING DEVICE

Filed April 13, 1922

2 Sheets-Sheet 2

UNITED STATES PATENT OFFICE.

JULIUS MINTZ, OF NEW YORK, N. Y.

SHIFTER CLAMPING DEVICE.

Application filed April 18, 1922. Serial No. 552,169.

To all whom it may concern:

Be it known that I, JULIUS MINTZ, a resident of New York city, Bronx County, State of New York, and a citizen of the United States of America, have invented certain new and useful Improvements in Shifter Clamping Devices, of which the following is a specification.

This invention relates to improvements in clamping devices particularly arranged to firmly bind stacked sheets of cloth in order that tags or other means of identification can be applied by a sewing machine to each sheet without disarranging the pile.

15 I will now proceed to describe my invention in detail, the novel features of which I will point out in the appended claims, reference being had to the accompanying drawings, wherein:—

20 Fig. 1 illustrates a face view of my improved clamp, a portion of a pile of stacked sheets being illustrated as held thereby;

Fig. 2 is a sectional side view, the section being taken on a line 2—2 in Fig. 1;

25 Fig. 3 is an enlarged fragmentary sectional view, the section being taken on line 3—3 in Fig. 5;

Fig. 4 is a detail view illustrating the clamping lever and post, other parts being omitted;

30 Fig. 5 is a fragmentary face view looking from the left in Fig. 3;

Fig. 6 is a sectional fragmentary plan view, the section being taken on a line 6—6 in Fig. 2;

35 Fig. 7 is a fragmentary detail end view, illustrating one set of clamping jaws for securing the device to a support;

40 Fig. 8 is a face view, looking from the right in Fig. 7, of the clamping jaws only;

Fig. 9 is a fragmentary plan view of the uppermost beam of the clamping device; and

45 Fig. 10 is a fragmentary face view illustrating more fully the function of the clamping device.

The clamping device which I have designed is intended mainly for use in connection with a pile of superimposed layers of cloth to which identification tags or other labels are to be applied by sewing machines. The layers are piled so that the edges aline, or at least one edge. Each layer comprising the pile is turned down after the tag or label has been applied thereto in order that the next succeeding upper layer can have

applied thereto its label, the same being applied by hand or machine.

As herein embodied, my invention is comprised of a clamping post 11 carried by a slide-rest 12 movable longitudinally of a rail 13 secured, at each end, by clamping jaws 14 and 15, the jaw-member 15 being adjustable by means of a lead-screw 16, to a suitable support 17, be it a bench or the table for a sewing machine or stamping device. At its upper end, post 11 carries a beam 18 which is pivotally connected to post 11 by a pivot pin or screw 19. The beam 18 supports a resilient clip or arm 20 which is pivotally secured to beam 18 by a pin or screw 21. The rest 12 carries an arm 22 extending over the face of support 17, but out of contact therewith, a roller 23 being provided to facilitate the movement of the clamping head as a whole over the surface of the support.

The post 11 carries a plurality of spaced apart projections 24 designed to be acted upon by an eccentrically mounted disk 25 carrying an arm 26. The disk 25 carries a flange 27 to engage the projections 24. The disk 25 is pivotally connected by a screw 28 to bracket 29 carried by the slide rest 12, as can be seen in Fig. 3. The flange 27 on disk 25 is cut away at 30 and 31 (Fig. 4) to permit the projections 24 to pass through when the pressure device or disk 25 is moved to the position indicated in Fig. 4, or when handle 26 is moved to a position parallel with the axis of post 11. As can be seen, post 11 is provided with a slot 32 through which rail 13 passes, thereby preventing rotation upon the part of said post 11. The clamping jaw 14 and arm 22 are preferably made integral with their respective parts 13 and 12. The clamping jaw 15 is slidably mounted upon rail 13 by means of screws 33 which pass through slot 34 in the plate portion 35 of jaw 15. The lead screw is rotatably secured, at its upper end, to a lug 36 carried by rail 13. When screw 16 is manipulated, jaw 15 will be moved up or down to accommodate the thickness of the support 17.

The clamping head, indicated generally by A, in Fig. 2, is made movable longitudinally of its rail in order that said head can be moved up to a sewing machine (not shown), should same be carried by support 17. The goods to be marked or labeled are placed between beam 18 and arm 20, the disk

- 25 being positioned, as indicated in Fig. 4, after which the post 11 will be forced downwardly to cause arm 20 to firmly engage the pile of superimposed layers of cloth, indicated by B, whereupon arm 26 will be moved to the right or left, causing flange 27 to engage an adjacent projection or lug 24, thereby imposing pressure upon the post and also locking the post in depressed position.
- 10 10 To apply identification marks to the layers, the pile will be lifted up or folded back, leaving the bottom layer flat. The clamp will now be moved toward the sewing machine indicated by C Fig. 10 and the 15 lowermost layer placed upon the plate 37 and sewed after which the clamping device will be moved back, pulling the layer to which the label or the like has been sewed. When the clamping device is drawn back, 20 the end of the lowermost layer will drop through an opening 38 in support 17. The next upper layer will now be pulled off the rolled back layers and the clamping device moved up to the machine, as hereinbefore 25 explained. The second layer will be dropped through opening 38 after the label has been applied thereto. This operation will repeat until all the layers have been labeled. The clip 20 serves to hold the rolled back 30 layers as indicated in Fig. 10.
- What I desire to secure by Letters Patent is:—
1. In a clamping device, a rail, a rest 35 slideable longitudinally thereof, a post carried by the rest arranged for vertical adjustment, and means carried by the rest arranged to exert downward pressure upon the post.
  2. In a clamping device, a rail, a rest 40 slideable longitudinally thereof, a post carried by the rest arranged for vertical adjustment, projections carried by the post and means carried by the rest arranged to engage a projection and exert downward pressure upon the post.
  3. In a clamping device, a rail, a rest 45 slideable longitudinally thereof, a post carried by the rest arranged for vertical adjustment, projections carried by the post, and an eccentrically mounted disk carried by the rest, arranged to engage a projection and exert downward pressure upon the post, and means to operate the disk.
  4. In a clamping device, a rail, a rest 50 slideable longitudinally thereof, a post carried by the rest arranged for vertical adjustment, projections carried by the post, and an eccentrically mounted disk carried by the rest, a post carried by the rest arranged for vertical adjustment, projections carried by the post, and an eccentrically mounted disk carried by the rest, a flange carried by the disk to engage a projection and exert downward pressure upon the post, and means to operate the disk.
  5. In a clamping device, a rail, a rest 55 slideable longitudinally thereof, an arm carried by the rest, a post carried by the rest arranged for vertical adjustment, a beam pivotally connected at one end to one end of the post, and means to exert a downward pressure upon the post.
  6. In a clamping device, a rail, a rest 60 slideable longitudinally thereof, an arm carried by the rest, a post carried by the rest arranged for vertical adjustment, a beam pivotally connected at one end to one end of the post, means to exert a downward pressure upon the post, and a resilient clip pivotally connected to said beam.
  7. In a clamping device, a rail, a rest 65 slideable longitudinally thereof, a post carried by the rest arranged for vertical adjustment, projections carried by the post, and an eccentrically mounted disk carried by the rest, a flange carried by the disk to engage a projection and exert downward pressure upon the post, and means to operate the disk, said flange being provided with 70 openings therethrough for the passage of said projections when said disk is moved to a position to permit the post to be adjusted vertically.
  8. In a clamping device, a rail, a rest 75 slideable longitudinally thereof, a post carried by the rest arranged for vertical adjustment, projections carried by the post and an eccentrically mounted disk carried by the rest, a flange carried by the disk to engage a projection and exert downward pressure upon the post, means to operate the disk, said flange being provided with openings 80 therethrough for the passage of said projections when said disk is moved to a position to permit the post to be adjusted vertically, and means at each end of said rail to secure same to a table or the like.
  9. In testimony whereof I hereunto affix my 85 signature.

JULIUS MINTZ.
